UNITED STATES PATENT OFFICE

107,589

DESIGN FOR A SADDLE

Charles R. Waldron, Norwalk, Ohio, and Roland W. Faulhaber, Alma, Mich.

Application April 7, 1937, Serial No. 68,607

Term of patent 7 years

To all whom it may concern:

Be it known that we, Charles R. Waldron and Roland W. Faulhaber, citizens of the United States, residing at Norwalk, in the county of Huron and State of Ohio, and Alma, in the county of Gratiot, State of Michigan, respectively, have invented a new, original, and ornamental Design for a Saddle, of which the following is a specification, reference being had to the accompanying drawings, forming part thereof.

In the drawings, Figure 1 is a plan view of a saddle embodying our new design;

Figure 2 is a side elevational view thereof.

The important feature of the design is the sloping or flared portion along the rear edge of the saddle of a color contrasting with the remaining portion of the saddle as shown.

We claim:

The ornamental design for a saddle, substantially as shown and described.

ROLAND W. FAULHABER.
